UNITED STATES PATENT OFFICE.

CYRUS HANKINS, OF BALTIMORE, MARYLAND, ASSIGNOR TO THE SYMINGTON COMPANY, OF NEW YORK, N. Y., A CORPORATION OF MARYLAND.

SIDE FRAME.

Application filed May 28, 1925, Serial No. 33,482. Renewed August 20, 1928.

This invention relates to side frames for railway car trucks, and more particularly to such frames formed from sheet metal blanks.

One of the principal objects of my invention, generally considered, is the formation of wrought metal side frames formed with means for supporting the bolster springs whereby it is possible to eliminate the use of a spring plank as well as other improved

10 features.

An object of my invention is the provision of a pressed metal truck side frame formed from a blank of sheet metal folded upon itself and united along portions of its lower 15 edge and at other portions by rivets or the like, said frame comprising compression, tension and bolster column portions and provided with a member resting on the upper portion of the tension member and connected 20 to the bolster column portions for the purpose of supporting the bolster springs.

Another object of my invention is the provision of a frame for railway car trucks formed with compression, tension and bolster 25 column portions, said portions being so spaced that a window opening for the reception of the bolster is provided, the lower portion of said window opening being partially enclosed by a spring pan connected to 30 adjacent portions of the bolster columns and extending therebetween whereby the necessity of a spring plank is obviated.

A further object of my invention is the provision of a sheet metal side frame formed 35 with compression, tension and bolster column portions, the lower portions of the bolster columns being connected by plates, which plates are extended or bulged outwardly to form supports for embracing the bolster 40 springs, the lower edges of said plates being formed with inwardly extending flanges adapted to underlie the bolster springs and preferably provided with spring positioning 45 bosses thereon.

A still further object of my invention is the provision of spring pans connected to the bolster column portions of railway car trucks provided with flanges supported on the tension members of said trucks and 50 underlying the bolster springs and upward extensions along the bolster columns forming bolster guide portions.

An additional object of my invention is

the formation of a novel connection between journal boxes and the corresponding ends of 55 an associated side frame for railway car trucks, said connection involving the employment of a flange or flanges on the journal box and cooperating abutting portions on the frame, said cooperating portions being 60 preferably riveted together or otherwise suitably connected.

Other objects and advantages of the invention relating to the specific details of construction and arrangement of parts will be 65 become apparent as the description proceeds.

Referring to the drawings illustrating my invention, the scope whereof is defined by the claims:

Figure 1 is a side elevation showing a side 70 frame embodying my invention,

Figure 2 is a plan view partly in horizontal section on the line 2—2 of Figure 1,

Figure 3 is a transverse sectional view on the line 3—3 of Figure 1,

Figure 4 is a transverse sectional view on the line 4—4 of Figure 1 and looking in the direction of the arrows,

Figure 5 is a transverse sectional view on the line 5—5 of Figure 1 and looking in the 80 direction of the arrows,

Figure 6 is a transverse sectional view on the line 6—6 of Figure 1 looking in the direction of the arrows,

Figure 7 is a transverse sectional view on 85 the line 7—7 of Figure 1,

Figure 8 is a side elevation showing a modified embodiment of my invention,

Figure 9 is a plan view partly in section on the line 9—9 of Figure 8,

Figure 10 is a transverse sectional view on the line 10—10 of Figure 8,

Figure 11 is a horizontal sectional view on the line 11—11 of Figure 8 and looking in the direction of the arrows,

Figures 12 and 13 are transverse sectional views on the correspondingly numbered lines of Figure 8 looking in the directions of the arrows.

Referring to the drawings in which similar reference characters designate like parts in the several views and considering first the embodiment of my invention illustrated in Figures 1 to 7 inclusive, there is shown a side frame 1 constructed from a single 100 sheet of metal by bending a blank thereof

to form a plurality of compression member portions 2, tension members 3 and truck column or strut portions 4.

Between the compression portions 2 and 5 tension members 3 and truck column portions 4 is formed a window opening 5 adapted for the reception of a bolster. The side frame blank besides being apertured to form the window opening 5 is also preferably provided with triangular openings 6 and 7, as is usual. After bending the blank along the portion corresponding to the upper side of the compression member 2, the lower edges of the diagonal portions 8 of the tension member 3 are preferably secured together by rivets 9 or other suitable securing means.

A preferred construction of the compression and tension members is to provide inwardly extending flanges thereon so that 20 said members are substantially box shape in section as illustrated particularly in Figures 3 to 7 inclusive.

The inwardly extending flanges on the diagonal portions 8 of the tension member 25 are preferably continued as downward extensions 10 abutting along a central longitudinal plane and the connecting rivets 9 pass therethrough.

The bolster column or strut members 4, in 30 the present instance, are formed as upright extensions from the upper flanges on the tension members and the downward flanges on the compression portions, said bolster column or strut portions being preferably connected by rivets 11.

The intermediate or substantially horizontal portion 12 of the tension member 3 is adapted to receive spring seating pans or plates 13, one pan extending on the outer 40 and one on the inner side of the frame, as illustrated particularly in Figure 2, for holding the bolster springs in operative positions. Said plates 13, in the present instance, comprise upright portions 14 extending between and connected to the bolster column portions 4 by a plurality of rivets 15, said rivets also serving as additional connecting means between the portions of the bolster columns.

50 In the present instance the ends of the upright portions 14 of the spring pans 13 are extended upwardly at 16 along the bolster column portions and formed with outwardly extending flanges 17 serving as bolster guides. The extensions 16 are also preferably connected to the bolster column portions by rivets 18.

The spring pans 13 are preferably provided with substantially horizontal flange 60 portions 19 resting on the upper flanges of the tension portions 3 of the side frame and preferably formed with spring bosses 20 for properly positioning the bolster springs (not shown). The upright portions 14 of 65 the spring pans are preferably curved or

bulged outwardly so as to accommodate the bolster springs and yet snugly embrace them, said springs at their inner sides being held in position by upward extensions 21 from the upper inwardly extending flanges on the 70 tension portions 3. Said flanges or extensions 21 are preferably united by a plurality of rivet means 22. At each end on the side frame there is connected a journal box 23, said journal box being preferably formed 75 with flange portions 24 embracing the ends of the side frame and connected to the sides thereof by a plurality of rivets 25.

The flanges 24 on the journal boxes are preferably offset below the diagonal portions 8 of the tension members 3 so as to closely embrace the extensions 10 from the flanges thereof and are connected thereto by a plurality of rivets 26.

From a consideration of Figures 1, 2, 4 85 and 5 particularly, it will be apparent that the journal boxes are very rigidly secured to the ends of the side frame as the flanges on said journal boxes are formed to snugly fit against the sides and extensions from the 90 side frame and the top or roof of the journal box snugly fits against the outer portions of the lower flanges on the ends of the side frame.

By virtue of the spring pan construction 95 under the window opening 5 provision is made for snugly holding the bolster springs in operative positions, said springs being supported in position around the spring bosses 20 and held against tipping by the upright portions 14 of the spring pans and the extensions 21 from the tension members 3.

Referring now to the embodiment of my 105 invention illustrated in Figures 8 to 13 inclusive, a side frame 1^a of similar construction is illustrated, said frame, as in the previous embodiment comprising box-like compression portions 2^a and tension portions 3^a. The bolster column portions 4^a, however, 110 are of a slightly different formation from the bolster column portions 4 of the first embodiment, that is, they are substantially box-like in cross section as the compression and tension members, rather than being formed of flat sections riveted together.

The outer or side walls 27 of said bolster column portions are formed by merely slightly offsetting continuations of the side walls of the compression and tension members. All of said frame members are formed with inwardly extending flanges. As in the first embodiment, the lower edges of the diagonal portions 8^a of the tension members are connected together by rivets 9^a extending through extensions 10^a from the inwardly extending flanges on the tension portions 8^a.

As in the previous embodiment, spring pan members or plates 13^a are provided, upright portions 14^a thereof extending between and 130

riveted at their ends to the bolster column portions 4^a, as illustrated, the rivet means being designated by the reference character 15^a. In the present instance the spring pan members 13^a are not continued upwardly to form bolster guide portions as the bolster columns being of rectangular or box section are of substantially the proper size for that purpose. It is preferable, however, to provide said bolster columns 4^a with wear plates 17^a serving as bolster guides, said wear plates being suitably connected to the bolster columns 4^a by rivet means 18^a or the like.

As in the first embodiment of my invention, the spring pans 13^a are provided with inwardly extending flange portions 19^a resting on the upper flanges of the tension portions 3^a and adapted to underlie and support the bolster springs (not shown). Said flange portions 19^a are preferably provided with spring bosses 20^a for properly centering the springs.

In the present instance, the inner edges 28 of the flange portions 19^a are curved, as illustrated particularly in Figures 9 and 11, to conform with the upwardly extending portions 21^a from the tension portions 3^a which, in the present instance, are not continued substantially vertically from the inwardly extending flanges on the upper edge of the tension portions but are curved gradually from said flanges upwardly and inwardly and are also curved transversely, as illustrated particularly in Figure 11, to more closely embrace the bolster springs and provide separating embossed portions 29 therebetween.

As in the previous embodiment, the extensions 21^a between bolster springs are connected together by a plurality of rivet means 22^a. At the ends of the frame there are connected journal boxes 23^a, said journal boxes being illustrated as of somewhat different construction from those of the first modification, that is, they are each provided with an inwardly extending lug 24^a which is embraced between and riveted to the extensions 19^a from the diagonal portions 8^a of the tension members 3^a. The rivet means for this purpose is designated as 26^a.

The top or roof of each journal box instead of being connected to the frame by flanges from the journal box is connected thereto by a channel or U-shaped member 30 which rests on the inwardly extending flanges at the lower portions of the ends of the side frame and is connected to said flanges and to the roof of the corresponding journal box by upright rivets 31. The arms or upwardly extending flanges 32 from the channel shaped connecting member 30 are secured to the side walls of the frame at the ends thereof by a plurality of rivets 33 or other suitable connecting means, as illustrated. In this way the journal boxes are

securely fastened at the ends of the frame without the necessity of providing them with the elaborate flange construction illustrated in the first embodiment.

In view of the aforescribed construction, it will be apparent that I have provided means for supporting the bolster springs so that the use of a spring plank of any kind may be dispensed with. Inasmuch as the lower portion of the window or bolster opening has been partially closed by the spring pans, the bolsters used with such side frames will be made with removable outside guide lugs in order to enter the window opening.

The two halves of the side frame, as will be apparent, are very rigidly secured together not only by the rivets 9 and 9^a connecting the lower portions of the diagonal tension members but also by the rivets 22 and 22^a connecting the extensions from the upper portions of the tension members. The rivets 11 and 15 in the first embodiment also serve for connecting the portions of the frame together. In this way a very rigid construction is secured.

Having thus described the invention, I claim:

1. A car truck side frame comprising compression and tension members spaced at intermediate portions thereof by bolster column portions forming a window opening therebetween, and spring seating pans with portions extending below the window opening and resting on the top of the tension member, and other portions joining the bolster column portions.

2. A car truck side frame comprising compression and tension members spaced at intermediate portions thereof by bolster column portions forming a window opening therebetween, and spring seating pans with portions extending below the window opening and resting on the top of the tension member, and other portions, angularly disposed with respect thereto, joining the bolster column portions and partially closing the window opening.

3. A car truck side frame comprising compression and tension members spaced at intermediate portions thereof by bolster column portions forming a window opening therebetween, and spring seating pans with portions resting on the tension member and adapted to underlie the bolster springs, and other portions extending between the bolster column portions and adapted to embrace the bolster springs therebetween.

4. A car truck side frame comprising compression and tension members spaced at intermediate portions thereof by bolster column portions forming a window opening therebetween, and spring seating pans with portions supported on the tension member, formed with spring bosses adapted to position the bolster springs, and angularly dis-

- posed curved portions connected at their ends to the bolster column portions.
5. A car truck side frame comprising compression and tension members spaced at intermediate portions thereof by bolster column portions forming a window opening therebetween, and webs connecting the lower portions of the bolster columns and partially closing the window opening, said webs flanges on the lower edges of the tension portions and having portions thereof extending downwardly therefrom, a journal box mounted at each end of the frame and provided with flanges embracing said downwardly extending portions, and means extending through said flanges and downwardly extending portions for connecting said boxes and frame. 70
- 10 being provided with inwardly extending flanges underlying the bolster openings and supported on the tension member.
6. A car truck side frame comprising compression and tension members spaced at intermediate portions thereof by bolster column portions forming a window opening therebetween, and plates connected to the lower portions of the bolster columns and adapted to embrace the bolster springs. 80
- 15 7. A car truck side frame comprising compression and tension members spaced at intermediate portions thereof by bolster column portions forming a window opening therebetween, and plates riveted to the lower portions of the bolster columns and adapted to embrace the bolster springs, said plates being formed with flanges resting on the tension member and adapted to underlie said bolster springs. 85
- 20 8. A car truck side frame comprising compression and tension members spaced at intermediate portions thereof by bolster column portions forming a window opening therebetween, and plates connected to the lower portions of the bolster columns at their ends and bulged outwardly to embrace the bolster springs. 90
- 25 9. A car truck side frame comprising compression and tension members spaced at intermediate portions thereof by bolster column portions forming a window opening therebetween, and plates connected to the lower portions of the bolster columns at their ends and bulged outwardly to embrace the bolster springs, those portions of the plates adjacent the bolster columns being extended upwardly as bolster guides. 95
- 30 10. A car truck side frame comprising compression and tension members spaced at intermediate portions thereof by bolster column portions forming a window opening therebetween, and plates connected to the lower portions of the bolster columns at their ends and bulged outwardly to embrace the bolster springs, those portions of the plates adjacent the bolster columns being extended upwardly as bolster guides, and flanges extending inwardly from intermediate portions of the plates, resting on the tension member and adapted to support and position the bolster springs. 105
- 35 11. A car truck side frame comprising spaced side walls each of which has a plurality of compression and tension portions connected at their ends, inwardly extending flanges on the lower edges of the tension portions and having portions thereof extending downwardly therefrom, a journal box mounted at each end of the frame and provided with flanges embracing said spaced side walls, portions of said flanges being inwardly offset to abut and embrace the downwardly extending portions, and means extending through said flanges, side walls and downwardly extending portions for connecting said boxes and frame. 110
- 40 12. A car truck side frame comprising spaced side walls each of which has a plurality of compression and tension portions connected at their ends, inwardly extending flanges on the lower edges of the tension portions and having portions thereof extending downwardly therefrom, a journal box mounted at each end of the frame and provided with flanges embracing said spaced side walls, portions of said flanges being inwardly offset to abut and embrace the downwardly extending portions, and means extending through said flanges, side walls and downwardly extending portions for connecting said boxes and frame. 115
- 45 13. A car truck side frame comprising spaced side walls each of which has a plurality of compression and tension portions connected at their ends, inwardly extending flanges on the lower edges of the tension portions and having portions thereof extending downwardly therefrom, a journal box mounted at each end of the frame and provided with a flange lying side by side with and connected to said downwardly extending portions, and a channel shaped member between the walls of the frame at each end, the web thereof being united to a journal box and the flanges being united to the adjacent walls of the frame. 120
- 50 14. A car truck side frame comprising spaced side walls, a journal box mounted at each end thereof and connected thereto by a U-shaped member between the walls of the frame, the intermediate portion of the member being joined to the adjacent journal box and the upstanding flanges thereof being united to the adjacent side walls of the frame. 125
- 55 15. A car truck side frame comprising inner and outer walls arranged in spaced relation, each of said walls having a plurality of compression and tension portions with truck column portions separating intermediate portions thereof, the compression and tension portions being provided with flanges projecting inwardly of the side walls, portions of the flanges on the tension members being provided with downward extensions adjacent diagonal end portions thereof and with upward extensions adjacent intermediate portions thereof, and means rigidly securing all of said extensions together. 130
- 60 16. A car truck side frame comprising inner and outer walls arranged in spaced relation, each of said walls having a plu-

rality of compression and tension portions, 5 bolster column portions separating intermediate portions of said compression and tension members, said tension members being formed with diagonal end portions and intermediate substantially horizontal portions, the diagonal end portions thereof be-

ing provided with abutting downward extensions and the intermediate portions being provided with abutting upward extensions, 10 and rivet means connecting all of said extensions.

In testimony whereof I affix my signature.
CYRUS HANKINS.
